UNITED STATES PATENT OFFICE.

RAYMOND N. KLASS, OF DES MOINES, IOWA.

GARTER AND GARMENT SUPPORTER.

Application filed September 24, 1920. Serial No. 412,602.

To all whom it may concern:

Be it known that I, RAYMOND N. KLASS, a citizen of the United States, and a resident of Des Moines, in the county of Polk 5 and State of Iowa, have invented certain new and useful Garters and Garment Supporters, of which the following is a specification.

The object of my invention is to provide 10 a garter of very simple construction, having a member adapted to encircle the leg, and provided with fastening devices at each end, and to provide a downwardly hanging member having at its upper end a fastening device 15 adapted to coact with said first two fastening devices, and provided at its lower end with a garment engaging member.

A further object is to provide such a garter in which the leg encircling member 20 is made of two parts, and having two of said downwardly hanging members.

Still a further object is to provide a garter having two downwardly extending members connected at their upper ends, and having 25 at their upper ends a fastening device designed to be detachably, and quickly and easily connected with a coacting fastening device for securing the downwardly hanging member to a support.

With these and other objects in view my 30 invention consists in the construction, arrangement and combination of the various parts of the device, whereby the objects contemplated are attained, as hereinafter more 35 fully set forth, pointed out in my claims and illustrated in the accompanying drawings, in which:

Figure 1 shows a perspective view of a 40 garter embodying my invention.

Figure 2 shows a side elevation of the 45 downwardly hanging member.

Figure 3 shows a plan view of one of the 50 fastening devices.

Figure 4 shows a plan view of the coacting 55 fastening device.

Figure 5 shows a front elevation of a 60 slightly modified form of my garter.

Figure 6 shows a front elevation of one 65 of the parts of the leg encircling member 50 of the garter shown in Figure 5.

Figure 7 shows a front elevation of an 70 other modified form.

Figure 8 shows the fastening device 75 adapted to coact with the form of garter 55 shown in Figure 7.

In the accompanying drawings I have used the reference numeral 10 to indicate generally a strip or band of elastic webbing forming a part of my garter and designed to encircle the leg of the wearer. 60

Secured to one end of the strip 10 is a fastening device, such as is shown, for instance, in Figure 4, indicated by the reference character 11.

The other end of the strip 10 is folded 65 and lapped over the body of the strip and is detachably secured thereto by an ordinary sliding fastening device 12.

Supported by the overlapped portion and the body of the strip 10 is a fastening device 70 11, similar to that already described.

For coacting with the leg encircling strip 10 I have provided a downwardly hanging member 13, provided at its upper end with a circular enlarged pad portion 13^a into 75 which is secured a fastening device similar to the button device commonly used on gloves, and shown in Figure 3, said device being indicated by the reference character 14. 80

The upper end of the member 13 is provided with a circular portion for the purpose of forming a pad of sufficient size to protect the leg from coming in contact with the metal portion of the members 11 and 14 as clearly shown in Figures 1, 2 and 5 of the drawing. The diameter of this enlarged portion or pad should be such that the outer corners of the fasteners 11 will be substantially even with the outer edges of the 90 said circular pad so that as the members 11 swing about the buttons 14, the outer corners of the said members 11 will travel or ride on the outer edges of the said pad, thereby holding the outer edges of said pad 95 adjacent to the leg of the wearer, and thereby preventing the said edge from turning up or under and causing the outer edge to be curled or wrinkled so that it will not be pressed into the flesh by the tension of the 100 members 10 or 16 and 17. Any swinging movement of the members 10 or 16 caused by the contraction and expansion of the muscles of the leg will have a tendency to smooth out the outer edge of the pad, the 105 pad, as shown in Figure 2, being somewhat exaggerated for thickness as the said pad is comparatively thin as actually constructed.

At the lower end of the downwardly 110

hanging member 13 is a suitable fastening device 15 of any desired form or kind for fastening to a stocking or half hose.

It will be noted that in the garter just described, either end of the leg encircling member 10 may be quickly and easily detached from the downwardly hanging member 13.

It makes no difference whether the garter shown in Figure 1 is used as a right or as a left.

With the construction illustrated, both ends of the strip 10 may be quickly and easily detached from the member 13, and the member 13 may be left attached to the garment.

It is sometimes easier and preferable to disconnect the garter from the garment.

In Figure 5 I have shown a modified form 20 of my garter which comprises the relatively long strip of elastic webbing 16, having at each end a fastening device 11 similar to that already described.

A relatively shorter strip of elastic webbing 17 is provided having at its opposite end fastening devices 11.

With the form of my garter illustrated in Figures 5 and 6 I employ two downwardly hanging members 13 each similar in construction to that already described. In the complete garter shown in Figure 5 the strip 17 is interposed between the ends of the strip 16 and the fastening devices 11. The opposite ends of the strips 17 are fastened 35 to the respective fastening devices 14 on the respective downwardly hanging members 13. The fastening devices 11 at the ends of the members 16 are also fastened to the fastening devices 14 on the respective downwardly hanging members 13, all as shown in Figure 5.

It will be seen that with the form of my invention illustrated in Figures 5 and 6, the stocking or half hose may be supported 45 at two different points spaced from each other.

The garter may be unfastened at either of the fastening devices 14, or if desired the fastening devices 15 on the lower ends 50 of the members 13 may be left attached to the garment, and the strips 17 and 16 may be removed.

The garter shown in Figures 5 and 6 may be used either as a right or left.

55 If desired, the member 13 may be left secured to the garment and either end of the strip 16 may be unfastened for removing the garter from the leg.

In Figures 7 and 8 I have shown a 60 slightly different form of my invention. Two strips 18 of elastic webbing have fastening devices 15 similar to those already mentioned at their lower ends, and are connected at their upper ends to a common member 19. Secured to the upper end of the

member 19 is a fastening device 11, similar to those already described.

The double downwardly hanging device just described, is designed to be connected with the fastening device 14 on a member 70 20, which may be fastened to a garment in any ordinary way.

The construction shown in Figures 7 and 8 is particularly designed for use for children.

I desire particularly to call attention to the advantages of the form of device shown in Figure 1, some of which have been already referred to. There is a single pivot to which both ends of the leg encircling member, and the upper end of the fastener member are 80 detachably secured. With an ordinary garter having a pad to which the leg encircling member is sewed, the garter is fitted to be worn with the webbing arranged at a particular angle to the pad. If the pad is not 85 placed in exactly the right position on the leg, the parts will buckle and rub. The garter is really adapted for use with one size of leg only and does not readily adjust itself to the leg but in many instances will 90 buckle as suggested.

With the form of garter shown in Figure 1, where both ends of the leg encircling member are secured to a pivot, such member will naturally and automatically adjust itself to 95 the shape of the leg. With a pad garter there is no stretch in the pad and when the leg expands or contracts with muscular action, the garter binds, whereas with my structure free expansion and contraction is 100 possible entirely around the leg. The webbing may be readily replaced when worn. The amount of sweat absorbing and heating surface of material is reduced to a minimum so that the garter is cooler and more 105 comfortable than would otherwise be the case.

Another advantage of my construction lies in the fact that the pivot member 14 is mounted in a protecting pad of such diameter that it will lie beneath the exposed metallic parts of the member 11 in such a manner that the said parts will not come in contact with the leg of the person wearing the supporter.

110 Some changes may be made in the details of the construction and arrangement of my improved garter, without departing from the real spirit and purpose of my invention, and it is my intention to cover by my claims any 120 modified form of structure or use of mechanical equivalents which may be reasonably included within their scope.

I claim as my invention:

1. An improved apparel garter comprising 125 in combination a strip of elastic webbing designed to encircle the wearer's leg, a fastening device secured to each end thereof, a circular pad, a hose supporting member fixed to the lower portion of said pad, a button 130

- fixed to and projecting from the central portion of the pad, said fastening devices and said button so shaped and arranged that the fastening devices are pivotally connected 5 with the button, the said pad being of such size that it will underlie the two fastening devices and protect the leg of the wearer from coming in contact with either of said fastening devices in any position of their 10 pivotal movement, said parts being so shaped and arranged that both ends of the elastic webbing are attached to said button and no tension is applied to the sides of the pad that might cause it to bind upon the wearer's 15 leg, and said parts being also so arranged that during the pivotal movement of the said fastening devices relative to the pad they will tend to smooth out the pad and prevent it from creasing or wrinkling.
- 20 2. An improved apparel garter comprising in combination a strip of elastic webbing designed to encircle the wearer's leg, a fastening device secured to each end thereof, a circular pad, a hose supporting member fixed 25 to the lower portion of said pad, a button fixed to and projecting from the central portion of the pad, said fastening devices and said button so shaped and arranged that the fastening devices are pivotally connected 30 with the button, the radius of said pad being substantially equal to the distance of the farthest corner of said fasteners to the center of said button so that it will underlie the two fastening devices and protect the leg of the wearer from coming in contact with 35 either of said fastening devices in any position of their pivotal movement.
3. A device of the character described comprising a circular pad, a band, a garment supporter attached to and projecting 40 from said pad along the radius of the pad, and fastening means between the ends of said band and the center of the pad constructed and arranged to permit the ends of said band to extend exactly along radii of 45 the pad at various angles and adjust themselves independently of each other, said fastening means lying within the confines of the periphery of the pad.

Des Moines, Iowa, December 29, 1919.

RAYMOND N. KLASS.
